US00D535629S

(12) **United States Design Patent** (10) Patent No.: **US D535,629 S**
(45) Date of Patent: **** Jan. 23, 2007**

(54) **CIRCUIT BREAKER LOCKOUT DEVICE**

2003/0154751 A1 * 8/2003 Turek 70/203

(75) Inventors: **Scott Kalous**, Libertyville, IL (US);
Mike Brojanac, Jackson, WI (US)

* cited by examiner

(73) Assignee: **Master Lock Company**, Oak Creek,
WI (US)

Primary Examiner—Selina Sikder

(**) Term: **14 Years**

(74) Attorney, Agent, or Firm—Calfee, Halter & Griswold
LLP

(21) Appl. No.: **29/226,423**

(57) **CLAIM**

(22) Filed: **Mar. 29, 2005**

The ornamental design for a circuit breaker lockout device,
as shown and described.

(51) LOC (8) Cl. **13-03**

DESCRIPTION

(52) U.S. Cl. **D13/178**

FIG. 1 is a perspective view of the circuit breaker lockout
device of the present invention;

(58) Field of Classification Search D13/178,

FIG. 2 is a front view of the circuit breaker lockout device
shown in FIG. 1;

D13/160; 70/203; 200/43.01, 43.11, 43.14,
200/43.15, 43.16, 43.19, 43.21; 361/72

FIG. 3 is a back view of the circuit breaker lockout device
shown in FIG. 1;

See application file for complete search history.

FIG. 4 is a bottom view of the circuit breaker lockout device
shown in FIG. 1,
